UNITED STATES PATENT OFFICE.

BENJAMIN B. DUDLEY, OF VISALIA, CALIFORNIA.

COOKER.

Application filed January 17, 1922. Serial No. 529,871.

To all whom it may concern:

Be it known that I, BENJAMIN B. DUDLEY, a citizen of the United States, and a resident of Visalia, county of Tulare, and State 5 of California, have invented a new and useful Cooker, of which the following is a specification.

The present invention relates to improvements in cookers and its particular object is 10 to provide a cooker to be used in combination with a motor vehicle and constructed in such a manner that it receives its heat from the exhaust gases of the vehicle engine. A further object of the invention is 15 to provide improved means for applying this heat. Further objects and advantages of my device will appear as the description proceeds.

With these objects in mind I have illustrated the preferred forms of my invention in the accompanying drawings, in which Figure 1 is a side view of an automobile having my cooker attached thereto; Figure 2 a longitudinal cross section through one 25 form of the cooker; Figure 3 a top plan view of the same cooker; Figure 4 a side view, partly in cross section, of a modified form of a cooker; and Figure 5 a top plan view of the same. While the devices illustrated are the preferred forms of my invention, it will be understood that various 30 changes or modifications may be made within the scope of the claims hereto attached without departing from the spirit of the invention.

My cooker (1) is shown in Figure 1 as secured to the running board of the automobile (2). The cooker as illustrated in Figure 2 comprises a receptacle (3) having 40 hollow walls and a hollow bottom filled preferably with asbestos or some other heat insulating material. The open top of the receptacle is tapered as shown at (4) so as to provide a seat for the cover (6), which 45 is also hollow and filled with asbestos, as at (7), and has a tapered body as shown at (8) adapted to be received on the seat (4), the flange (9) of the top being secured to a projection (11) of the receptacle by means 50 of studs (12) and wing nuts (13). Horizontal angle irons (14) are secured to the inner wall of the receptacle so as to form a seat for the cooking vessel (16), which is preferably dimensioned in such a manner 55 as to leave a free space between the cooking vessel and the receptacle, but which

extends from its seat upward into contact with the top of the receptacle so that none of the liquid (17) surrounding the cooking vessel can enter the same.

To heat the liquid I use the exhaust gases of the engine, which are led for this purpose from the exhaust manifold, not shown in the drawing, into the pipe (18) secured underneath the vehicle and ordinarily carrying the exhaust gases to the muffler (19). As shown at (21), this pipe (18) is tapped and the exhaust gases are diverted into a transverse pipe (22) connecting, as shown at (23), with an upright pipe (24) extending through the fender (26) into the space (27) underneath the cooking vessel (16). From here it is led through a series of concentrically disposed tubes (28) into the upright pipe (29) passing through the bottom of the receptacle and the fender and communicating with the pipe (31) leading back into the main pipe (18) and carrying the exhaust gases into the muffler (19).

A modified form of this device is shown in Figure 4, in which the arrangement of the cooking vessel is somewhat different from that shown in Figure 2. In this device the receptacle is provided with a closed top (36) having a plurality of apertures (37) consisting of an annular recess (38) and a tapered portion (39) leading from the same into the receptacle and adapted to form a seat for the tapered flange (41) of the cooking vessel (42). The lid (43) of the cooking vessel has a tapered body portion (44) fitting on the tapered flange of the vessel and has a horizontal flange (46) fitting in the recess (38) of the receptacle. A plurality of U-shaped clamps (47) rest with one leg on the lid and with the other leg on the top of the receptacle, and are held in firm engagement with the lid and the receptacle by means of studs (49) and wing nuts (51). It will be seen that in this modification a firmer connection is obtained between the cooking vessel and the lid since the pressure of the heated liquid will force the cooking vessel into firmer contact with the lid along the tapered portion (41), the lid being prevented from moving by the clamps (47).

I claim:

1. In combination with the engine exhaust of a motor vehicle, a cooker comprising a 110 receptacle having a tapered opening in its top, a cooking vessel having a tapered top

- flange adapted to fit in said opening, a lid for the vessel having a tapered body engaging the flange of the vessel and a horizontal flange resting on the top of the receptacle, clamping means for holding the lid in place, and means for guiding the exhaust gases of the engine into the receptacle for heating the cooking vessel.
2. In combination with the engine exhaust of a motor vehicle, a cooker comprising a receptacle holding a liquid and having a tapered opening in its top, a cooking vessel having a tapered top flange adapted to fit in said opening, a lid for the vessel having a tapered body engaging the flange of the vessel and a horizontal flange resting on the top of the receptacle, clamping means

for holding the lid in place and means for guiding the exhaust gases through the liquid whereby the contents of the cooker are heated.

3. A cooker comprising a receptacle holding a liquid and having a tapered opening in its top, a cooking vessel having a tapered top flange adapted to fit in the opening, a lid for the vessel having a tapered body engaging the flange of the vessel and a horizontal flange resting on the top of the receptacle, clamping means for holding the lid in place, and means for heating the liquid, the pressure of the liquid serving to force the vessel into closer contact with the lid.

BENJAMIN B. DUDLEY.
